FORM FOR USE IN MAKING CEMENT-
FIBER BOARDS

Armin Elmendorf, Winnetka, Ill.

Application August 3, 1950, Serial No. 177,443

4 Claims. (Cl. 25—119)

1

The present invention relates to forms or molds particularly adapted for use in a continuous process of making so-called cement-fiber board, although it is not confined to that specific use.

The primary purpose of the invention is to permit wood or other organic fibers that may be several inches long and are coated with a Portland cement or gypsum binder to be fashioned into board material of predetermined width and indefinite length which is cut into individual panel lengths; each panel remaining in an individual form until cured or set. In this way every panel may be of uniform texture from one end to the other and, after being molded, it is protected against damage until it becomes strong and hard. Due to the nature of the forms used heretofore for such products there have always been large variations in the texture and density of the individual boards or panels at their ends and edges; and therefore such boards have not been commercially satisfactory.

In carrying out my invention I construct a form composed of only a bottom wall and two parallel side walls, so that the mold cavity is open at the top and at both ends. Any number of forms may be placed end to end to provide a trough of any desired length. The forms are so constructed that the continuous sheet may be cut across the width thereof by rapidly moving saws at the meeting lines of consecutive forms, thereby leaving in each individual form an individual panel with perfect, square end edge faces. These forms may then be placed in stacks, with each form serving as a caul to compress the panel in the next lower form until it has a predetermined thickness which is maintained until the final setting and hardening of the binder.

The various features of novelty whereby the present invention is characterized will hereinafter be pointed out with particularity in the claims, but, for a full understanding of the invention and of its objects and advantages, reference may be had to the following detailed description taken in connection with the accompanying drawing, wherein:

Figure 1 is an end view of one of my improved forms or molds, with the center broken out; Fig. 2 is a top plan view of such form, broken out at both the longitudinal and transverse centers; Fig. 3 is an end view of two forms that have been filled and are positioned one upon the other to start the building of a stack, only a fragment of each form being shown; Fig. 4 is a top plan view showing, on a much smaller scale, a plurality of

the forms arranged end to end to create a single, long trough-like form; Fig. 5 is a side view, on the same scale as Figs. 1-3, showing fragments of two of the forms which meet in Fig. 4; Fig. 6 is an end view of a fragment of a form provided with a wear-resisting lining; and Fig. 7 is an end view of a fragment of another modified form.

Each form is composed of a flat bottom wall 1 and two parallel side walls, 2 and 3. The side walls are preferably sturdy ledges or bars and are somewhat shorter than the bottom wall. In the arrangement shown the side walls terminate at equal distances from the ends of the bottom wall. Therefore, when two of the forms are placed end to end, regardless of which end of one meets the other form, similar slots or gaps, 4, 4, respectively, appear in the side walls of the composite form, directly opposite each other. The bottom wall is preferably rabbeted transversely 10 beyond the ends of the side walls, as at 5, so that when two forms are placed end to end, the slots 4 are, in effect, continued down into the bottom wall of the composite mold. With this arrangement the saw teeth may project down below the lower face of the mat during the sawing operations.

In the under side of the bottom wall are rabbets that reduce the marginal portions 1^a, at opposite sides, in thickness over widths equal to the widths of the side walls; thereby leaving intact the large central part 1^b that is just as wide as the internal width of the form. The part 1^b may therefore be regarded as a downward projection on the bottom wall adapted to enter a like form when the two forms are set one on the other; and the marginal portions 1^a may be regarded as shoulders on the upper of two forms, adapted to rest on top of the side walls of the under form.

The height of the side walls is equal to the thickness of the panel to be molded, plus the thickness of the downward projection 1^b. Therefore, when a form is nested in another, the effective mold cavity in the lower form has exactly the same cross-sectional shape and area as does the product to be made; and the bottom of the upper form constitutes a caul to bear down on and effect the desired compression of a rudimentary panel in the lower form.

The molds are intended to be placed end to end in a machine that moves the composite form lengthwise while a continuous mat of cement-coated fibers is built up therein. Then, as each individual form reaches a predetermined position, the mat is severed transversely between

that form and the next one. The freed form may then be removed and an empty form be added at the trailing end of the line of forms. Each form so removed carries a rudimentary panel with it. Then, when the removed forms are stacked upon each other, the final shaping of the panels completes itself. The panels are taken out of the forms only when they have become firm and hard.

Because cements, such as Portland cement and gypsum, set due to the formation of crystals from an aqueous solution thereof, there has been a generally accepted belief that cement fiber board, using such cements, cannot be made commercially as continuous mats which are then cut into panel lengths; for the reason that substantial setting of the cement, before setting, was deemed essential. I have found, however, that by using my long, slotted form and a rapidly moving saw, panel-length sections may be cut off squarely and cleanly as soon as they have been molded into shape.

At the time a panel is severed from the mat it should be substantially thicker than the finished product. In Fig. 3 the rudimentary panel A in the upper form is shown as being thick enough to protrude a little through the top of the form. The panel A¹ in the lower form, on the other hand, has been compressed to give it the thickness which the finished product is intended to have. When a third form is added to the stack, panel A will be compressed thereby to the same thickness as panel A¹. Since only the end edges of the panels are left exposed when molds containing panels are stacked, cement mortar may be trowelled into such edges, preferably immediately after stacking; thereby preventing undue loss of moisture while setting and leaving the edge faces less fibrous than before.

The form is preferably made of wood and, to facilitate the removal of panels therefrom, the inner surfaces may be oiled as in conventional concrete form work. On the other hand, the interior of the form, especially the bottom wall, may have its inner surfaces composed of a hard plastic, such as a phenol-formaldehyde overlay, that does not adhere to the cement. In Fig. 6 there is such a lining or overlay 6 on all interior surfaces of the form.

If desired, the form may be so constructed that the bottom wall constitutes a tie between the two side walls of the next lower form in a stack. Thus, as shown in Fig. 7, the top of each side wall is cut away along the outer edge over a substantial width, as at 7^a, thereby leaving an upstanding rib 7^b along the inner edge. Each part 8^a of the bottom wall, corresponding to part 1^a in the first species, has along its outer edge a downwardly projecting rib 8^c, that is just as wide and as deep as the excision in the top of the overlying side wall. When forms are stacked the parts 8^a rest on ribs 7^b of the next lower form, while ribs 8^c rest on the depressed surfaces 7^a of the latter form.

It will therefore be seen that I have created a novel form or mold that makes possible the production of cement-fiber board panels in a unique and efficient way, and insures that the texture at the ends of each panel is the same as elsewhere throughout the length of the panel; this being due to the fact that the panels are not molded individually but as part of a continuous mat, along with the further fact that each panel may remain in an individual mold until it is a finished product.

I claim:

1. An open ended form for use in manufacturing cement-fiber board, consisting of a bottom wall having square ends and two parallel side walls that are somewhat higher than the thickness of the board to be produced, the side walls being slightly shorter than the bottom wall, the bottom wall having on the under side a downwardly protruding portion as wide as the distance between the side walls, and the thickness of said protruding portion being equal to the difference between the height of the side walls and the thickness of said board.

10 15 20 25 30 35 40 45 50 55 60 65 70 75 80 85 90 95

2. A form as set forth in claim 1, wherein each side wall is symmetrically disposed with respect to the bottom wall, whereby, whenever two forms are set end to end and filled with cement-fiber mixture, there is in each composite side wall a slot directly opposite the slot in the other composite wall, thereby permitting a saw to be moved crosswise of the forms through the slots to sever a board that extends through both forms.

3. An open-ended form for use in manufacturing cement fiber board, consisting of a bottom wall having square ends and two side walls each of which is slightly shorter than the bottom wall whereby, when two such forms are placed end to end, a slot is created between each side wall in one form and the near end of the corresponding side wall in the other form at a time when the two bottom walls are touching each other to form a continuous wall, wherein the under side of the bottom wall is shaped to fit over the top and down both the inner and outer sides of the side walls of a like mold when two such molds are placed one on top of the other.

4. An open-ended form for use in manufacturing cement fiber board, consisting of a bottom wall and two side walls each of which is slightly shorter than the bottom wall whereby, when two such forms are placed end to end, a slot is created between each side wall in one form and the corresponding wall in the other form at the time the two bottom walls are contacting each other, wherein the bottom wall contains in the top, beyond the ends of the side walls, transverse rabbets for creating downward extensions of the slots between the opposed ends of the two meeting forms.
